(57) **CLAIM**

The ornamental design for a lighting fixture, as shown and described.

DESCRIPTION

This application contains subject matter which is related to the subject matter of concurrently filed U.S. Design patent application Ser. No. 29/612,023, entitled "Recessed Lighting Fixture" by Mark A. Gaynor; U.S. Design patent application Ser. No. 29/612,024, entitled "Lighting Fixture Having an Illumination Effect" by Mark A. Gaynor, which applications are hereby incorporated in their entirety herein by reference.

FIG. 1 is a right perspective view of a lighting fixture according to a first embodiment of the new design;

FIG. 2 is a left perspective view thereof;

FIG. 3 is a front elevational view thereof;

FIG. 4 is a right side elevational view thereof;

FIG. 5 is a left side elevational view thereof;

FIG. 6 is a top view thereof;

FIG. 7 is a bottom view thereof;

FIG. 8 is an enlarged view of detail 8 of FIG. 1;

FIG. 9 is an enlarged view of detail 9 of FIG. 2;

FIG. 10 is an enlarged cross-sectional view taken along line 10-10 of FIG. 3;

FIG. 11 is a front elevational view of a second embodiment of the lighting fixture according to the new design in which the sole difference between this embodiment and the first embodiment is the symbolic break lines shown in the figure;

FIG. 12 is a right perspective view of a third embodiment of the lighting fixture according to the new design in which the stipple shading indicates a contrasting appearance;

FIG. 13 is a left perspective view thereof;

FIG. 14 is a front elevational view thereof;

FIG. 15 is a right side elevational view thereof;

FIG. 16 is a left side elevational view thereof;

FIG. 17 is a top view thereof;

FIG. 18 is a bottom view thereof;

FIG. 19 is an enlarged view of detail 19 of FIG. 12;

FIG. 20 is an enlarged view of detail 20 of FIG. 13;

(Continued)

FIG. 21 is an enlarged cross-sectional view taken along line 21-21 of FIG. 14; and,

FIG. 22 is a front elevational view of a fourth embodiment of the lighting fixture according to the new design in which the sole difference between this embodiment and the third embodiment is the symbolic break lines shown in the figure. The cross-section of the lighting fixture in FIG. 10 corresponds to cross-sections along the length of the opening in the lighting fixture shown in FIG. 3.

The cross-section of the lighting fixture in FIG. 21 corresponds to cross-sections along the length of the opening in the lighting fixture shown in FIG. 14.

FIGS. 11 and 22 are shown with symbolic break lines through the lighting fixture. The appearance of any portion of the article between the break lines forms no part of the claimed design.

The broken lines in the drawing disclosure illustrate portions of the lighting fixture that form no part of the claimed design.
